(57) **CLAIM**

The ornamental design for a faucet set, as shown and described.

DESCRIPTION

FIG. 1 is a perspective view of a faucet set showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is the first operational embodiment thereof; and,

FIG. 9 is the second operational embodiment thereof.

The broken lines are included for the purpose of illustrating a portion of the faucet set that forms no part of the claimed design.
